(57) **CLAIM**

The ornamental design for a display screen or portion thereof with icon, as shown and described.

DESCRIPTION

FIG. 1 is a front view of a first embodiment of a display screen or portion thereof with icon, showing our new design; FIG. 2 is a front view of a second embodiment of a display screen or portion thereof with icon, showing our new design; and,

FIG. 3 is a front view of a third embodiment of a display screen or portion thereof with icon, showing our new design. The outer perimeter illustrated by a pair of broken lines depicts a display screen or portion thereof and forms no part of the claimed design.
